UNITED STATES PATENT OFFICE.

WALTER F. VAN GUYSLING, OF ALBANY, NEW YORK, ASSIGNOR OF ONE-HALF TO JAMES W. HALLENBEK, OF SAME PLACE.

SIGHT-FEED LUBRICATOR.

SPECIFICATION forming part of Letters Patent No. 425,590, dated April 15, 1890.

Application filed July 29, 1889. Serial No. 319,034. (No model.)

To all whom it may concern:

Be it known that I, WALTER F. VAN GUYSLING, of the city and county of Albany, in the State of New York, have invented new and useful Improvements in the Construction of Sight-Feed Lubricators, of which the following is a specification.

My invention relates to improvements in the construction of sight-feed lubricators and the mode of securing together the several parts of the same; and the object of my invention is to simplify the construction of this class of devices and to facilitate the separation and securing together the several parts of the same. This object I attain by the means illustrated in the accompanying drawings, which are herein referred to and form part of this specification, and in which—

Figure 1 is a front elevation of an upwardly feeding lubricator made in accordance with my invention. Fig. 2 is a like elevation of a downwardly-feeding lubricator. Fig. 3 is a vertical section of Fig. 1. Fig. 4 is a plan view of Fig. 1. Fig. 5 is a plan view of the upper head detached from the lubricator. Fig. 6 is a side elevation of the cross-bar or nut and its set-bolt detached from the lubricator. Fig. 7 is a side elevation of the lubricator shown in Fig. 1; and Fig. 8 is a vertical section of the upper portion of Fig. 7, showing the outlet for the lubricant.

As represented in the drawings, the cage of my lubricator consists of an upper head A, a lower head B, side links C, and a cross-bar D, provided with a set-bolt E.

The upper head A is preferably made in the form of an elliptic block, which has in its lower face an annular recess for containing an elastic gasket 1, which forms a cushion for the upper end of the glass tube F. In the upper face of said upper head is a groove 2, which extends across the major diameter of said head, and preferably said groove is made wider at its middle than at its ends. From the center of the recess in the lower face of said head there is made an outlet-opening 3, which joins a horizontal branch 4 of said opening for the purpose of affording an outlet for the lubricant which flows upwardly in the tube F. The outlet-opening 4 passes through

a screw-threaded nipple 6, on which the regulating-valve H is secured. In the opposite ends of said head there are formed vertical grooves 5, which correspond in position with the groove 2, and into which the side bars C 55 are fitted to lie, as shown in Fig. 7, and preferably in such manner that said side bars will finish flush with the surface of the head A. An outflow-pipe G, which conveys the lubricant to the point where it is to be applied, is connected to the outlet branch 4 by means of a regulating-valve H.

The lower head B has substantially the same form as the upper head, excepting that the lower head is made without the groove 2 65 of said upper head, and that the lower head is provided with a conical nipple 7, which contains a central opening 6, that forms a continuation of the inlet-passage 8, through which the lubricant is conducted into the interior of the device. A supply-pipe J, which conveys the lubricant from a reservoir wherein it is contained, is provided with a regulating-valve I, whereby the inflow of lubricant into the device can be governed as occasion may 75 require, and said supply-pipe forms a communication with the inlet-passage 8 of the lower head.

The cross-bar D is fitted snugly into the groove 2 in the upper head A and is made to 80 conform to the shape of said groove. The opposite ends of said cross-bar are each provided with a concave seat 9, for receiving the hooked upper end of the side links C, which is made to fit into said seat. Said cross-bar is also provided with a centrally-located set-bolt E, which is fitted to bear against the lower side of the groove 2, so that when said bolt is screwed inwardly into said cross-bar the latter will be correspondingly raised in said groove. 85

The side links C are each made to enter into its appropriate groove 5 in the ends of the upper and lower heads, and each is provided with a hook 10 at its upper end, as shown in Fig. 3, and with a hook 11 at its lower end. 95 The hook 10 is made with a convex seat 13, which fits into the concave seat of the cross-bar D, so as to engage therein in such manner that the link C can have a swinging movement in respect to said cross-bar, with the convex 100

seat 13 serving as a pivotal center for said movement. The hook 11 is preferably made with an undercut bevel face that is fitted to engage in a corresponding seat in the lower face of the lower head B.

The glass tube F, which affords the means for determining whether the lubricator is properly performing its work, should have its opposite ends made parallel with each other, so that both ends will obtain a fair bearing on the elastic gasket 1, which is appropriated thereto, and so that a steam-tight joint will be formed at each end of said tube.

The mode of assembling and securing together the several parts of my lubricator is as follows: The cross-bar D, with the set-bolt E screwed out so that its point will be within the cross-bar, is inserted in the groove 2. The glass tube F is fixed between the heads A and B, so that the opposite ends of said tube will rest upon the elastic gaskets, that are specially appropriated thereto. Then the side links C are attached in place, first at one end of said heads and then at the opposite end, and in attaching the last one of said links the seat 13 is placed in the concave seat 9 of the cross-bar D, while the lower end of the link is swung outward. The two heads are forced toward each other until the hook 11 of the partially-attached side link will enter the notch formed in the lower head B to receive it. Then by screwing down the set-bolt E the heads A and B will be forced toward each other and press the ends of the tube F into the respective gaskets 1, so as to form steam-tight joints at those points.

In Fig. 2 the device is simply inverted in

position, so that the lubricant, instead of rising by reason of its inferior gravity as compared with the water always contained in the tube, when the device is used in the position shown in Fig. 1 will pass downwardly; but it will be seen that when used in either position the supply-pipe J and outflow-pipe G maintain their several purposes.

My lubricator does not operate in any manner differently from the same kind of lubricator when constructed in a different manner, and it should be understood that my invention does not relate to a new mode of operation, but is limited to a new construction of lubricators.

What I claim as my invention, and desire to secure by Letters Patent, is—

In a lubricator, the combination of two heads, each being provided with an elastic annulus or gasket and each being fitted to receive side links for connecting said heads, a tube fixed between said heads with its opposite ends bearing on said gaskets, side links having hooked ends at both extremities, the hooked ends at one extremity being fitted to engage on one of said heads and the hooked ends of the opposite extremity being fitted to engage on opposite ends of a movable cross-bar, and a cross-bar provided with a set-bolt that is fitted to bear against the opposite head, so as to bind the several parts together, as and for the purpose herein specified.

WALTER F. VAN GUYSLING.

S. B. BREWER.

Correction in Letters Patent No. 425,590.

It is hereby certified that the name of the assignee in Letters Patent No. 425,590, granted April 15, 1890, upon the application of Walter F. Van Guysling, of Albany, New York, for an improvement in "Sight-feed Lubricators," was erroneously written and printed "James W. Hallenbek," whereas said name should have been written and printed *James W. Hallenbeck*; and that the said Letters Patent should be read with this correction therein that the same may conform to the record of the case in the Patent Office.

Signed, countersigned and sealed this 29th day of April, A. D. 1890.

[SEAL.]

CYRUS BUSSEY,
Assistant Secretary of the Interior.

Countersigned:

ROBERT J. FISHER,
Acting Commissioner of Patents.
